HYDRAULIC DOUBLE ACTING METAL DRAWING PRESS

Filed July 19, 1934

UNITED STATES PATENT OFFICE

2,067,265

HYDRAULIC DOUBLE-ACTING METAL-DRAWING PRESS

Walter Ernst, Mount Gilead, Ohio, assignor, by mesne assignments, to The Hydraulic Press Corporation, Inc., Wilmington, Del., a corporation of Delaware

Application July 19, 1934, Serial No. 736,062

15 Claims. (Cl. 113—45)

This invention relates to hydraulic presses and, in particular, to such presses arranged for drawing metal blanks into articles of various shapes, the press including means for clamping the metal blank while the drawing operation is taking place.

One object of my invention is to provide a hydraulic double-acting press having a drawing piston and a clamping piston arranged to move substantially simultaneously into position during the working stroke, until the blank is clamped, whereupon the drawing piston continues the work of forming the article.

Another object is to provide a press of the above type wherein, after the drawing operation has been completed, the drawing piston first moves away from the work, which is held in place by the clamping piston until the drawing piston engages a member interconnecting it and the clamping piston and carries the latter along with it and out of engagement with the blank and the formed article.

Another object is to provide a hydraulic double-acting metal-drawing press having a clamping piston so arranged that the fluid discharged from the main cylinder during the working stroke actuates the clamping piston before leaving the circuit.

Another object is to provide a hydraulic double-acting metal-drawing press having a main drawing piston and a clamping piston with piston heads so related in area that the pull-back side of the main piston head has an area equal to the total area of the clamping piston head or heads, plus an additional area which is sufficient, at the usual working pressure, to raise the platen and clamping mechanism against the force of gravity.

Another object is to provide a hydraulic double-acting metal-drawing press wherein the pull-back side of the drawing piston is directly connected to the chamber above the clamping piston head, so that the clamping piston will be forced downward by the action of the fluid discharged from beneath the main drawing piston head, and held down for a period even after the fluid is reversed; until the drawing piston moves upward sufficiently to overcome the downward force exerted on the clamping piston whereupon it carries the clamping mechanism upward along with its own mechanism.

Another object is to provide a hydraulic double-acting metal-drawing press having a drawing piston and a clamping piston so arranged that the clamping piston is actuated by fluid discharged from beneath the drawing piston in

such a manner that both pistons move toward the work piece substantially together, means being provided for preventing the drawing piston from moving ahead of the clamping piston, such as by providing choking means to retard the motion of one piston relative to the other.

Another object is to provide hydraulic double-acting metal-drawing press of the above described type, wherein the clamping devices are provided with means for adjusting the clamping pressure so as to exert a predetermined force upon the blank during the drawing operation.

Another object is to provide a hydraulic double-acting metal-drawing press of the above described type, wherein the fluid proceeding toward or away from the main drawing cylinder will exert its pressure upon the clamping piston, tending to hold it in a clamping position until the main piston itself pulls the clamping piston away from the work piece by the application of greater force.

Another object is to provide a hydraulic double-acting metal-drawing press having a main drawing piston and platen arranged to engage a clamping piston in such a manner that the clamping piston tends to push against the platen during the working stroke and be pulled away from the work piece by the platen during the return stroke.

In the drawing:

The figure is a somewhat diagrammatic front elevation, partly in section, of a hydraulic double-acting metal-drawing press arranged according to my invention, together with a simplified circuit for actuating it.

Referring to the drawing in detail, the figure shows one embodiment of my invention consisting of a hydraulic press having a base 1, which is connected by the tie rods 2 to a top member 3, as by the nuts 4 engaging the threaded portions 5 thereof. The base 1 is provided with any suitable die 6 having a forming portion 7 of a shape suitable for the production of the particular form of article desired. A bore 8 therefrom leads to a pipe 9, which may be connected to a suitable source of compressed air in order to provide means for ejecting the finished article from the forming portion 7 of the die 6. The blank or metal plate from which the article is to be produced is indicated by the reference numeral 10.

The top member 3 of the press is so formed as to include a main drawing cylinder 11 and a pair of clamping cylinders 12 arranged on either side thereof. The number of the clamping and drawing cylinders 11 and 12 is immaterial, and it will

be understood that a greater or lesser number may be used as is most convenient for the particular conditions encountered. The open ends of the cylinders 11 and 12 are closed by glands 13 and 14 respectively, engaging the packings 15 and 16 to prevent the escape of fluid from these cylinders.

Passing through a bore in the gland 13 is the main drawing piston rod 17 which terminates at 10 its upper end in a main piston head 18 and at its lower end in the platen 19. Arranged beneath the latter is a die member 20 of corresponding but opposite configuration to that of the die portion 7 of the die 6, so that the two 15 portions 7 and 20 cooperate to form the finished article from the metal blank 10 held between them.

In a similar manner the clamping plungers 21 pass through bores in the glands 14 and at their 20 lower ends are attached to a tie member 22, which interconnects them. To the tie member 22 is secured the clamping member 23, as by the bolts 24. A blank holder 25 is placed upon the blank 10 and has an aperture 26, through which 25 the die portion 20 may pass in proceeding downward during its working stroke. The clamping member 23 at its lowest position comes to rest on the opposite side of the blank holder 25 from the blank 10.

30 The double-acting main drawing piston head 18 has a working face 27 and an annular pull-back or withdrawal face 28, whereas the clamping pistons 21 have piston head surfaces 29. In the preferred form of my invention, the pull-back area 28 is equal to the combined area of the clamping head surfaces 29, increased by an amount sufficient to enable it to lift the weight of its own mechanism plus that of the clamping mechanism at the ordinary working pressures.

40 The platen 19 drivingly engages the tie member 22 along the flanged or shouldered portion 30 thereof so that the former will drive or move the latter in one direction. Accordingly, by this driving engagement, the platen 19 on its upward 45 stroke will lift the tie member 22, together with its associated plungers 21 and clamp member 23. The weight of these parts is lifted by the additional area given to the annular pull-back surface 28 in excess of the area on the clamping piston heads 29. The portion of the main drawing cylinder 11 beneath the pull-back surface 28 is directly connected to the clamping cylinders 12 by the passages 31 running therebetween.

From one of the clamping cylinders 12, the 55 port 32 opens into the conduit 33 leading to the two-way valve casing 34, from the opposite side of which the conduit 35 leads to the adjustable choke 36. Beyond it the conduit 37 joins the conduit 38 in a T connection, leading to what 60 is normally the suction port 39 of the pump 40 when the press is exerting a working stroke. The pressure port 41 during the same operation leads, by way of the conduit 42, to the port 43, opening into the space above the working surface 27 of the piston 18 in the main cylinder 11.

Beyond the junction of the conduits 37 and 38 70 is the check valve 44, opening in the direction of the port 39. On the opposite side of the check valve 44, the conduit 45 leads to devices for supplying additional fluid to the pump 40, as is necessitated by the difference in area between the working face 27 and the annular pull-back face 28 of the main piston head 18. In order to simplify the circuit these devices have not been 75 shown, since they form no part of the present

invention. Due to the difference in area mentioned, more oil will be discharged from the space above the piston surface 27 than from below the annular piston surface 28, and this excess fluid may also be discharged into the supply tank 46 by means forming no part of this invention. The means for accomplishing this purpose may be obtained by the use of the main cylinder relief and by-pass valve shown in my previous United States Patent 1,956,758, issued May 1, 1934. A large opening for the fluid on both the working and return strokes of the press may also be supplied through the use of the main cylinder check valve disclosed in my previous United States Patent 1,892,568 issued December 27, 1932. 15

Also leading from the suction port 39 of the hydraulic pump 40 is the conduit 47 which joins the check valve 44. The latter opens in the direction of one of the clamping cylinders 12 to the port 49, to which it leads by way of the conduit 50. 20

Leading from the port 51 of the other clamping cylinder 12 is the pipe 52, joining the relief valve 53 having an outlet pipe 54 leading to the tank 46. The relief valve 53 is provided with a plunger 55 which is urged in a closing direction by the spring 56. A pilot conduit 57 leads from the space above the plunger 55 to the suction port 39 of the hydraulic pump 40. The purpose of this pilot line 57 is to apply pressure to the relief valve plunger 55 so that it cannot move upward 30 and open the valve during the return stroke of the press (during which stroke the suction port 39 becomes a pressure port through the reversal of the flow of the pump 40). This danger might otherwise occur when the relief valve 53 was set 35 for low clamping pressure, in which case the fluid might pass out through the relief valve into the tank 46 and leave insufficient pressure to lift the moving parts of the press. The pilot line 57 applies pressure to the relief valve plunger 55 and 40 effectively prevents this action.

The two-way valve 34 is of a normally-open type, and consists of a valve rod 58, on which are mounted the spaced heads 59 and 60. The valve rod 58 is urged in an upward direction by the coil 45 spring 61, engaging the valve head 59. The valve rod extension 62 passes downward through the closure plug 63. Beyond the latter the valve rod extension 62 passes loosely through the bore 64 in the arm 65 attached to the clamping tie member 22, as by the bolts 66. The valve rod extension 62 is provided with an adjustable stop 67 which is adapted to be engaged by the arm 65 as the latter moves downward. This action in turn pulls the valve head 60 downward and closes the 55 communication between the pipes 33 and 35 through the two-way valve 34.

In the operation of the press in drawing articles of various shapes from metal blanks, the metal blank 10 is first placed upon the die 6, and 60 the die holder 25 is superimposed upon it. The pump 40 is then placed in operation so as to discharge fluid under pressure through the conduit 42 and the port 43 into the space above the piston head 18 within the cylinder 11.

This action causes the platen 19 to move downward. At the same time, the fluid displaced from the space beneath the piston head 18 is forced through the channels 31 into the clamping cylinders 12, causing the clamping plungers 21 likewise to move downward. To prevent the piston 18 and the platen 19 from moving downward more rapidly than the clamping plungers 21 and the clamping member 23, the choke valve 36 is closed to such a point that the passage of liquid is suffi- 75

ciently impeded to force the clamping plunger tie member 22 downward against the platen 19 by reason of the increased pressure within the clamping cylinders 12. The clamping member 23 and the upper die 20 thus continue to move downward together until the former engages the blank holder 25, whereupon it stops. The upper die 20, however, continues to move downward, forcing the central portion of the metal blank into the lower die portion 1 and forming the metal article.

When the clamp-member has proceeded downward to the desired distance, the arm 65 of the clamping tie member 22 engages the stop 67 on the valve rod extension 62 of the two-way valve 34, pulling it downward and interposing the valve head 60 between the ports leading to the conduits 33 and 35 respectively. The escape of fluid through the port 49 and the conduit 50 is prevented by the check valve 48 which opens only in the direction of fluid passing in the direction of the pump 40 to the righthand cylinder 12.

Consequently the only remaining means for the further escape of the fluid from the cylinders 12 and from the space beneath the piston head 18 in the cylinder 11, now that the two-way valve 34 is closed, consists in the port 51 and pipe 52 leading from the lefthand cylinder 12 to the relief valve 53. When the pressure within the latter has increased to the blow-off point, the plunger 55 rises against the urge of the coil spring 56 and against the pressure exerted by the fluid coming through the pilot line 57, discharging the subsequent fluid into the pipe 54 leading to the tank 46. The pressure within the clamping cylinders 12 thus forces the clamping member 23 firmly against the blank holder 25 and holds the blank 10 in a firm grip. The force with which the blank 10 is held may be adjusted by adjusting the loading of the plunger 55 of the relief valve 53.

The metal blank is now securely held while the upper die member 20 continues to move downward into the lower die portion 1, performing the drawing operation. This continued motion occurs because the area of the upper surface 27 of the piston head 18 is far larger than the area of the lower piston head surface 28.

When the drawing operation has been completed, the pump 40 is reversed so that its port 41 becomes the suction port and its port 39, the pressure port. The fluid under pressure now passes from the pump 40 through the conduit 47, the check valve 48, conduit 50 and port 49 into the righthand clamping cylinder 12. This fluid continues to pass through the passages 31 into the space beneath the piston head 18 and into the lefthand clamping cylinder 12. The force of this pressure fluid continues to force the clamping plungers 21 downward, thereby continuing to clamp the blank 10. Under the force of the pressure fluid against the annular surface 28 on the lower side of the piston head 18, the latter and the platen 19 move upward until the platen engages the shouldered portion 30 on the clamping tie member 22.

Due to the fact that the area of the lower annular surface 28 on the piston head 18 is greater than the combined areas of the clamping piston heads 29, the piston head 18 will continue to move upward and the platen 19 will lift the clamping tie member 22 despite the opposing force exerted by the clamping plungers 21.

The entire assembly of the drawing and clamping mechanisms will then move upward together at a rapid rate, since the speed of the

piston head 18 is augmented by the pressure of the fluid displaced by the upwardly moving clamping plungers 21. The assembly will continue to travel until its top position is reached, whereupon the pump 40 is shifted into its neutral position. Meanwhile the rising of the clamping tie member 22 and its arm 65 results in the release of the two-way valve rod 62. The two-way valve 34 then opens and permits the escape of pressure fluid therethrough from the clamping cylinders 12 and from the space beneath the piston head 18 in the main drawing cylinder 11. The metal article may now be ejected from the forming portion 1 of the die 6 through the action of compressed air admitted through the pipe 9 and the bore 8 therein.

As has been previously mentioned, the fluid displaced from beneath the piston head 18 will be of a lesser volume than the fluid displaced from above the piston head 18, due to the volume occupied by the piston rod 17. The means for ejecting the surplus oil through a main cylinder relief and by-pass valve has been omitted, as previously stated, in order to simplify the circuit and because it forms no part of the present invention, being the subject of one of applicant's previous patents. Fluid to supply a deficiency in volume will, however, be admitted through the pipe 45 and the check valve 44 into the suction port 39 of the pump 40.

It will be understood that I desire to comprehend within my invention such modifications as may be necessary to adapt it to varying conditions and uses.

Having thus fully described my invention, what I claim as new and desire to secure by Letters Patent is:

1. In combination in a hydraulic press, a pump circuit for providing pressure fluid, a pressing cylinder, a pressing plunger therein, a clamping cylinder, a clamping plunger therein, and means providing inter-flow of pressure fluid between said clamping plunger and one side of said pressing plunger, said pressing and clamping cylinders being so connected and arranged that the fluid discharged from the pressing cylinder during the working stroke flows into the clamping cylinder and actuates the clamping plunger.

2. In combination in a hydraulic press, a pump circuit for providing pressure fluid, a pressing cylinder, a pressing plunger therein, a clamping cylinder, a clamping plunger therein, and means providing inter-flow of pressure fluid between said clamping plunger in said clamping cylinder and one side of said pressing plunger in said pressing cylinder, the last-mentioned side of said pressing plunger having an area greater than the head area of said clamping plunger.

3. In combination in a hydraulic press, a pump circuit for providing pressure fluid, a pressing cylinder, a double-acting pressing plunger therein with its opposite sides connected to said pump circuit, a clamping cylinder, a clamping plunger therein, and means providing for the constant and uninterrupted inter-flow of pressure fluid between said clamping plunger in said clamping cylinder and one side of said pressing plunger in said pressing cylinder.

4. In combination in a hydraulic press, a pump circuit for providing pressure fluid, a pressing cylinder, a pressing plunger therein, a platen connected thereto, a pair of clamping cylinders adjacent said pressing cylinder, a clamping plunger in each clamping cylinder, a clamping

- member interconnecting said clamping plungers to be operated thereby, and means providing inter-flow of pressure fluid between said clamping plungers and said pressing plunger.
5. In combination in a hydraulic press, a pump circuit for providing pressure fluid, a pressing cylinder, a pressing plunger therein, a platen connected thereto, a pair of clamping cylinders adjacent said pressing cylinder, a clamping plunger in each clamping cylinder, and a clamping member interconnecting said clamping plungers to be operated thereby, said platen and said clamping member being adapted to drivingly engage one another by a contact in one direction only.
6. In combination in a hydraulic press, a pump circuit for providing pressure fluid, a pressing cylinder, a pressing plunger therein, a platen connected thereto, a pair of clamping cylinders adjacent said pressing cylinder, a clamping plunger in each clamping cylinder, a clamping member interconnecting said clamping plungers to be operated thereby, said platen and said clamping member being adapted to drivingly engage one another, means providing free inter-flow of pressure fluid between said clamping plungers and said pressing plunger, and means providing restricted flow of fluid between said clamping plungers and said pump circuit.
- 30 7. In combination in a hydraulic press, a double-acting pressing plunger, a platen connected thereto, a clamping plunger, a clamping member operated thereby, said platen and said clamping member being adapted to engage one another, and means for restricting the discharge of pressure fluid from around one of said plungers, whereby to maintain said platen and said clamping member in engagement with one another during the motion thereof.
- 40 8. In combination in a hydraulic press, a pump circuit for providing pressure fluid, a pressing cylinder, a double-acting pressing plunger therein with its opposite sides connected to said pump circuit, a platen connected thereto, a clamping cylinder, a clamping plunger therein, a clamping member operated thereby, said platen and said clamping member being adapted to drivingly engage one another, and means providing inter-flow of pressure fluid between said clamping plunger and one side of said pressing plunger, the last-mentioned side of said pressing plunger having an area greater than the head area of said clamping plunger by an amount sufficient to enable the pressure fluid to retract said pressing plunger and said clamping plunger against the gravitational and other opposing forces exerted thereon.
- 50 9. In combination in a hydraulic press, a double-acting pressing plunger, a clamping plunger, means providing inter-flow of pressure fluid between said clamping plunger and one side of said pressing plunger, and valve means adapted to control the flow of fluid with respect to the space around said clamping plunger.
- 55 10. In combination in a hydraulic press, a double-acting pressing plunger, a clamping plunger, means providing inter-flow of pressure fluid between said clamping plunger and one side of said pressing plunger, and valve means adapted to control the flow of fluid with respect to the space around said clamping plunger, said valve means being operated by the motion of one of said plungers.
11. In combination in a hydraulic press, a double-acting pressing plunger, a clamping plunger, means providing inter-flow of pressure fluid between said clamping plunger and one side of said pressing plunger, and valve means adapted to control the flow of fluid with respect to the space around said clamping plunger, said valve means being operated by the motion of said clamping plunger.
12. In combination in a hydraulic press, a double-acting pressing plunger, a clamping plunger, means providing inter-flow of pressure fluid between said clamping plunger and one side of said pressing plunger, valve means adapted to control the flow of fluid with respect to the space around said clamping plunger, and escape valve means adapted to open at a predetermined pressure and release fluid from the space around said pressing plunger.
13. In combination in a hydraulic press, a double-acting pressing plunger, a clamping plunger, means providing inter-flow of pressure fluid between said clamping plunger and one side of said pressing plunger, valve means adapted to control the flow of fluid with respect to the space around said clamping plunger, and escape valve means adapted to open at a predetermined pressure and release fluid from the space around said pressing plunger while said plunger-operated valve remains closed.
14. In combination in a hydraulic press, a double-acting pressing plunger, a platen connected thereto, a clamping plunger, a clamping member operated thereby, means providing inter-flow of pressure fluid between said clamping plunger and one side of said pressing plunger, and escape valve means associated with said clamping plunger to release the pressure fluid from the space therearound when the clamping pressure thereof reaches a predetermined amount.
15. In combination in a hydraulic press, a double-acting pressing plunger, a platen connected thereto, a clamping plunger, a clamping member operated thereby, means providing inter-flow of pressure fluid between said clamping plunger and one side of said pressing plunger, a tie member releasably interconnecting said pressing plunger and said clamping plunger, and escape valve means associated with said clamping plunger to release the pressure fluid from the space therearound when the clamping pressure thereof reaches a predetermined amount, said tie member being arranged to permit said platen to continue its motion after said clamping member has reached its clamping position.

WALTER ERNST. 65
